UNITED STATES PATENT OFFICE.

CHRIST CHRISTENSEN, OF INDIANAPOLIS, INDIANA, ASSIGNOR, BY MESNE ASSIGNMENTS, TO TRIUMPH VOTING MACHINE COMPANY, A CORPORATION OF NEW JERSEY.

COUNTER-ACTUATOR AND VOTER-COUNTER FOR VOTING-MACHINES.

1,074,311.

Specification of Letters Patent. Patented Sept. 30, 1913.

Application filed March 12, 1909. Serial No. 482,970

To all whom it may concern:

Be it known that I, CHRIST CHRISTENSEN, a citizen of the United States, residing at Indianapolis, in the county of Marion and State of Indiana, have invented certain new and useful Improvements in Counter-Actuators and Voter-Counters for Voting-Machines, of which the following is a specification.

10 The object of my invention is to provide a counting mechanism for voting machines capable of counting the number of voters actuating the machine and to provide an actuating mechanism therefor, the construction being such that the reciprocatory movement of an actuating element will produce complete rotary movement of the counter actuating element, and the construction also being such that two independent counting mechanisms 15 are provided with a single actuating element, with a connection between said element and one of the counters which is practically permanent, while the connection between said actuating element and the other of said 20 counters is readily separable so that said last mentioned counter may, from time to time, be conveniently reset to zero while the first mentioned counter remains in permanent engagement with its actuating element 25 so that it can not be readily reset to zero, thereby simultaneously producing two comparative registrations each of which will serve as a check upon the other.

The accompanying drawings illustrate my 30 invention.

Figure 1 is an elevation of the counter structure from its indicating side, the face plate or casing within or to which the structure is to be secured being omitted; Fig. 2 35 a section on line 2—2 of Fig. 1; Fig. 3 a section on line 3—3 of Fig. 1; Fig. 4 a section on line 4—4 of Fig. 2, and Fig. 5 a section on line 5—5 of Fig. 1.

In the drawings, 10 indicates a boxlike 40 structure or casing, the interior of which is preferably open at one side and at the end 10'. Mounted within casing 10, preferably within a frame 11, is a substantially permanently fixed counter mechanism 12 having a considerable number of counter elements 13 visible at one point, in the usual well known manner. I prefer, for this purpose, an entirely inclosed counter requiring

a complete rotation of an actuating element or shaft to produce an actuation of the 55 counter elements 13, the counter which I prefer being substantially that which I show in my Patent No. 793,178.

Journaled in casing 11 and passing through the counter 12 so as to engage the 60 internal actuating element of said counter, is a shaft 15 which, in that portion which passes through counter 12, as well as the end of said shaft, is polygonal in cross section so as to positively engage the actuating element of the counter mechanism. Secured to or formed integral with shaft 15 at one end, is a disk or arm 16 provided with a radial slot 17 adapted to receive a pin 18 carried by a reciprocatory actuator 19, passing 70 through a suitable opening 20 in the casing 10, the inner end of said actuator 19 being confined in its actuating plane between disk 16 and the adjacent end wall which closes 75 one end of casing 10.

Sleeved upon shaft 15 adjacent disk 16 is a sleeve 21 which is journaled in frame 11 and is provided at the end adjacent disk 16 with a cam 22 comprising oppositely extending arms which coact with a pair of stationary cam ribs 23, 23. The cam ribs 23, 23 are preferably connected by a pair of cross heads 24, 24, which, with the cam ribs, form a frame readily inserted in the frame 11, so as to form, between the cam ribs, a 80 receptacle for the locking cam 22, the end of pin 18 projecting into the space between the cam ribs 23, 23. Connected to sleeve 21 is one end of a light spring 25, the other end of which is attached to the casing 11, in 90 order to yieldingly hold the cam 22 in the position shown in full lines in Fig. 3.

The frame 11 is not coextensive with casing 10 but shaft 15 is projected practically through the entire length of said casing in 95 order to receive a counter 30 which is preferably of the same general character as counter 13, although it need not comprise as many counter elements, for the reason that its range need not be so great. The 100 counter 30 preferably should fit the casing 10 adjacent the open end 10' so that said casing 10 will prevent movement of the counter 30 except axially of the shaft 15 and such axial movement is normally prevented 105 by any readily withdrawal means, such for

instance as a collar 31 temporarily secured to the end of the shaft 15 by suitable means, such for instance as a thumb screw or set screw 32.

5 The operation is as follows: The structure is secured preferably inside of the casing 10 of the voting machine, said casing having a sight opening, or sight openings, through which the indicating portions of the counters 12 and 30 may be visible. A reciprocation of the operating member 10, by any suitable means, such for instance as suitable connection with the locking and unlocking lever of the voting machine, or an obscuring door or screen, will result in the following action: The upward movement of link 19 will cause pin 18 to move upward through slot 17 until the pin strikes cam 22 by which it will be deflected to the left (Fig. 4) and 10 will pass upward into the crotch between cam 22 and the left hand cam-rib 23; further upward movement of the link 19 will drive pin 18 upward so as to force the upper end of cam 22 to the right, but as soon 15 as the pin 18 passes beyond the upper end of cam 22 said cam will be automatically returned to normal position by spring 25, so that when pin 18 starts upon its downward movement it will engage cam 22 and be deflected by it to the right, thus continuing 20 rotation of the disk and shaft 15; continued downward movement of pin 18 will drive it between the right hand cam-rib 23 and the lower end of cam 22 so as to again rock said 25 cam upon its axis until pin 18 passes to its lowest position beyond the lower end of cam 22, whereupon said cam returns to normal position. A complete reciprocation of pin 18, therefore, will cause a complete rotation of shaft 15 thus causing a counting 30 actuation of both counters 12 and 30. At the end of the first use of the machine in an election both counters 12 and 30, if both have started at zero, should indicate the 35 same, and if there is a difference an inspection would reveal which counter was in error. For a second or any subsequent election, collar 31 will be withdrawn and counter 30 also withdrawn and reset to zero, and 40 then replaced. Previous to the next use of the apparatus a reading of counter 12 would be taken and recorded and thus serve as a check upon the subsequent operation of the two counters simultaneously.

I claim as my invention:

1. In a voting machine, the combination, 55 of a pair of associated counters, a common actuating element for said counters whereby both of said counters will be simultaneously and equally affected, means for substantially permanently maintaining the connection between said operating element and one of the counters.

2. In a voting machine, the combination, 60 of a pair of associated counters, a permanent operating means for said counters, and means permitting the ready dissociation of only one of said counters from said operating means.

3. In a voting machine, the combination, 65 of a suitable supporting structure, a counter-operating shaft journaled therein, a pair of independent counters both mounted on said shaft, one of said counters being so connected with said shaft as to be readily dissociated from the same.

4. In a voting machine, the combination, 70 of a suitable supporting structure, a counter-operating shaft journaled therein, a pair of independent counters both mounted on said 80 shaft, one of said counters being so connected with said shaft as to be readily dissociated from the same, a head carried by said shaft and provided with a radial slot, an actuating link having a pin entering said 85 slot, and a cam structure coöperating with said pin and comprising stationary cam members, a coöperating rocking cam member, and means for yieldingly holding said 90 rocking cam member in one position.

5. A counter, a shaft for operating the counter, a head carried by said shaft and provided with a radial slot, an actuating link having a pin entering said slot, and a cam structure coöperating with said pin and comprising stationary cam members, a coöperating rocking cam member, and means for yieldingly holding said rocking cam member in one position.

In witness whereof, I have hereunto set 100 my hand and seal at Indianapolis, Indiana, this seventeenth day of July, A. D. one thousand nine hundred and seven.

CHRIST CHRISTENSEN. [L. s.]
